UNITED STATES PATENT OFFICE.

WILLIAM A. BARNES, OF BRIDGEPORT, CONNECTICUT.

ELECTRICAL ALARM.

SPECIFICATION forming part of Letters Patent No. 395,112, issued December 25, 1888.

Application filed March 1, 1888. Serial No. 265,813. (No model.)

To all whom it may concern:

Be it known that I, WILLIAM A. BARNES, of Bridgeport, Fairfield county, Connecticut, have invented a new and useful Improvement 5 in Electrical Alarms, of which the following is a specification.

My invention relates to an alarm apparatus whereby signals are transmitted by means of interruptions in the line-circuit automatically produced after the apparatus is once started.

My invention consists, more particularly, in the construction and arrangement of the mechanism hereinafter set forth.

In the accompanying drawings, Figure 1 is a front elevation and general view of the apparatus. In this figure, for the sake of clearness, the circuit-wires are omitted. They are shown, however, and may be readily traced upon Fig. 2, which is a diagram or skeleton of the various connections. Fig. 3 is a view of the apparatus, showing the motor-gearing below the plate 38 in elevation and the parts above said plate in section on the line xx of Fig. 1. Figs. 4 and 5 show the circuit-closing device, controlled by the door, in two positions. Fig. 6 is a detail view.

Similar letters of reference indicate like parts.

At 1 2, Fig. 2, is the main line divided into 30 two branches, 3 4. Each branch 3 4 includes one of the coils of the differentially-wound magnet 5. This magnet, as shown in Fig. 1, is arranged in the box or case 6, which encloses the apparatus. Said box is provided 35 with a hinged door, 7. The magnet is supported on the free end of a leaf-spring, 8, which is secured to the box or case at 9. Said spring has an upwardly-extending arm, 10, to which is pivoted the armature 11 of magnet 5.

12 is a standard, also supported upon spring 8 and carrying a contact-plate, 13, above which is a spring-plate, 53.

At 14 is a hooked latch which is pivoted to standard 12, and which may be used, when desired, to hold the armature 11 in contact with said plate 53 and so limit the upward movement of said armature.

The ends of the coils of magnet 5 connect by wires 15 16, Fig. 2, with fixed spring-fingers 17 18. Between fingers 17 and 18 is

another fixed finger, 19, which, by means of wire 20, communicates with part 2 of main line.

21 is a disk of hard rubber, or other non-conducting material, supported in front of the 55 fixed plate 38 on a shaft, 39. Upon said shaft is a winding-gear, 41, and a spring, 42. The end of the shaft is squared to receive a key, so that by rotating said shaft the spring 42 may be wound up. Adjacent to disk 21 is a 60 fixed arm, 22, Fig. 1, and upon the face of said disk are two pins, 23 and 24.

Normally the pin 24 makes contact with the upper edge of arm 22, and the pin 23 presses together the spring-fingers 17 19 18, and this 65 is the condition of the parts when the apparatus is ready for operation. Consequently (see Fig. 2) there will be a closed circuit from main line at 1, through branches 3 4 and magnet 5 to wires 15 16, to fingers 17 18, to 70 finger 19, to wire 20, and to main line at 2.

25 is a spring-finger.

26 is another spring-finger, which is interposed between finger 25 and the periphery of disk 21. The end of finger 26 is bent or 75 curved, as shown, to enter a recess in the periphery of disk 21. Hence normally the fingers 25 and 26 are not in contact. Finger 25 connects with main line at 1 by wire 27. Finger 26 connects with main line at 2 by 80 wire 20. Consequently said fingers 25 26 are in shunt 27 25 26 20 from main line.

The disk 21, as already stated, is rotated by the shaft 29 and spring 42. Geared to said shaft is an escapement-wheel, 28, Fig. 1, having an anchor, 29. To the anchor 29 is attached a rod, 30, which, when held motionless, causes one of the anchor-pallets to engage with the teeth of the escapement-wheel 28, and so to prevent motion of the latter, and 90 hence of the disk 21. On the end of rod 30 is a pin with which engages a hook on the end of an arm, 31, which extends from the pivoted armature 32 of an electro-magnet, 33. One terminal of the coil of magnet 33 connects with armature 11 of magnet 5 by a wire, 34, Fig. 2. The other terminal connects by a wire, 35, with one pole of a local battery, 36. The other pole of said battery 36 connects by wire 37 with contact-plate 13 on standard 12. 100

Therefore included in local circuit with battery 36 are wire 37, contact-plate 13, armature 11, wire 34, magnet 33, and wire 35.

I will now explain the operation of the apparatus: A current coming over the main line 1 and passing through the oppositely-wound coils of magnet 5, obviously does not energize that magnet. Hence said current continues on through wires 15 and 16 to spring-fingers 17 18, finger 19, and wire 2, and so to line again at 2. Suppose now, however, that either branch 3 or 4 be interrupted or more resistance be interposed or more current applied in one branch than in the other. Then, clearly, the coils of magnet 5 will no longer balance one another, and the magnet under the influence of the predominating coil will be energized, and consequently will attract its armature 11; but when the armature 11 is attracted it closes contact with plate 13 and so establishes local circuit through magnet 33. Magnet 33 then attracts its armature 32, and so causes arm 31 to release rod 30. Anchor 29 is then no longer held and the escapement-wheel 28 and associated clock-train is free to operate, and hence to rotate the disk 21. Now, as the disk 21 (see Fig. 1) turns in the direction of the arrow, the pin 23 thereon, which has been holding the fingers 17 19 18 in contact, is carried to the left and these fingers, being of spring metal, separate. Therefore the circuit from main line at 1, magnet 5, wires 15 16, said fingers, wire 20, and main line at 2 is broken, and the magnet 5 is free to release its armature again; but the clock-work having now been started goes on. As the disk 21 rotates, the recess in its edge moves from under the end of finger 26, and this finger, now pressed upon by the circular part of the periphery, is so forced into contact with finger 25. Therefore main-line circuit is closed through 1, 27, 25, 26, 20, and 2. On the edge of disk 21 are formed indentations arranged in any desired succession, as shown in Fig. 1, into which the extremity of finger 26 descends as they move beneath it. The disk 21 is therefore a circuit-breaking wheel interposed in the main circuit, and by its rotation making and breaking said current, so as to produce an alarm through any known mechanism capable of being actuated in accordance with said interruptions at a distant point—as, for example, a central fire-station. To recapitulate, therefore, whenever the strength of the current on one branch, 3 or 4, of the main line becomes stronger than on the other branch, the magnet 5 closes local circuit through magnet 33, which releases the clock-train, which then rotates the disk 21. When the disk 21 begins to rotate, the existing circuit from main line through the apparatus is broken and a new circuit is established, and this new circuit is interrupted in some definite way by the action of the inequalities on the periphery of the revolving disk, so that an alarm is thus transmitted over main line to a distant station, which alarm may serve

in the usual way to indicate the location of the apparatus.

Returning now to Fig. 2, 43 is a branch 70 wire extending from wire 37, and 44 a similar wire extending from wire 34. Wire 43 connects with a contact-bracket, 45, Figs. 1 and 2, and wire 44 connects with a spring-finger, 46. Resting upon the bracket 45 is a 75 flat piece of insulating material, 47, Figs. 4 and 5, having a guide-slot, 48, which receives fixed guide-pins 49. Near one end of the piece of insulating material 47 is a slot, 50. On the edge of the door 7 is a spring-hook, 80 51, which, when the door is closed, engages in slot 50, and moves the piece of insulating material 47 between the spring-finger 46 and the top of the bracket 45, thus breaking circuit through the shunt 43 45 46 44, as shown in 85 Fig. 5. When the door is opened, the hook 51 draws the piece of insulating material 47 from between the spring-finger 46 and bracket 45, and thus allows said finger to meet said bracket and so establish circuit through the 90 aforesaid shunt. The effect of thus establishing circuit is to energize magnet 33 and start the alarm. In this way any tampering with the apparatus is prevented, inasmuch as it is necessary to open the door to get access 95 to the mechanism, and the operation of opening the door causes an alarm-signal, as above explained, to be transmitted.

The rotation of the disk 21, Fig. 1, is limited by the stop 24, which finally comes in contact 100 with the lower side of the arm 22, and so prevents further revolution of the disk.

The magnet 5 and the standard 12 are, as already stated, supported upon the spring-arm 8. In apparatus containing magnets with 105 spring-armatures it frequently happens that a blow upon the containing-box, or even a jarring of the building, causes a vibration of the armature sufficient to cause it to close contact with an adjacent fixed stop or plate, 110 and so to establish a circuit between armature and plate. In the present case the effect, obviously, would be to send a false alarm. By supporting the magnet 5 and standard 12 both on the same spring plate or arm 8 any jarring 115 is communicated equally to the body of the magnet and the standard 12, both moving simultaneously, and the spring 8 taking up the shock. There is consequently no tendency of the armature 11 to vibrate individually, and 120 in this way the accidental sending of alarms, as above described, is effectively prevented.

In practice I propose to conduct the wires 3 4 through various parts of a building, for example, to be protected. If the object be 125 fire-protection, I prefer to make said wires of fusible material, as fully set forth, as described in United States Letters Patent No. 378,078, granted to me on the 21st day of February, 1888. With wire thus constructed any excess 130 of heat will cause a fusing of the substance of the wire, and consequently a break in the circuit.

I claim—

1. The combination of a line, an electro-magnet having oppositely-wound coils, two branch circuits from said line and respectively including the coils of said magnet, a circuit-breaker interposed between the ends of said branch circuits and line, a local circuit including an electro-magnet, the armature of the magnet serving to hold the circuit-breaker in normal adjustment so long as the local circuit is open, and the armature of the oppositely-wound coils arranged to control the local circuit and through it the circuit-breaker, substantially as set forth. 45
2. The combination of the line 1 2, having branches 3 4, magnet 5, having oppositely-wound coils included in said branches, disk 21 and mechanism for rotating the same, contact-fingers, such as 17 18 19, communicating with branches 3 4 and with line, projection 24 on said disk, branch 27, including circuit-breaker 25 26, the said circuit-breaker placed in proximity to the periphery of said disk and actuated to make and break circuit by projections on said periphery, armature 11 of said electro-magnet, and a stop or catch engaging and arresting said disk mechanism and controlled to release said mechanism by said armature, substantially as described. 50
3. The combination of the line 1 2, having branches 3 4, magnet 5, having oppositely-wound coils included in said branches, disk 21 and mechanism for rotating the same, contact-fingers, such as 17 18 19, communicating with branches 3 4 and with line, projection 24 on said disk, branch 27, including circuit-breaker 25, the said circuit-breaker being placed in proximity to the periphery of said disk and actuated to make and break circuit by said disk, and in local circuit with a battery, 36, the armature 11 of said electro-magnet, contact-plate 13, and electro-magnet 33, the said magnet 33 having an armature, 32, controlling the rotating mechanism of disk 21, substantially as described. 55
4. The combination of the line 1 2, having branches 3 4, magnet 5, having oppositely-wound coils included in said branches, disk 21 and spring 42 for rotating the same, contact-fingers, such as 17 18 19, communicating with branches 3 4 and with main line, projection 24 on said disk, branch 27, including circuit-breaker 25, the said circuit-breaker being placed in proximity to the periphery of said disk and actuated to make and break circuit by said disk, escapement-gear 55 28 29 30 and in local circuit with a battery, 36, the armature 11 of magnet 5, contact-plate 13, and electro-magnet 33, the said magnet 33 having an armature, 32, controlling said escapement-gear, substantially as described. 60
5. In combination, a line, branches leading from the line and including oppositely-wound coils, a circuit-breaking wheel between the branches and the line, a shunt between the circuit-breaking wheel and line, a mechanism 65 for rotating said circuit-breaking wheel, and a local circuit comprising a battery, a circuit-closer, and an electro-magnet, the said magnet having an armature controlling said wheel mechanism, substantially as set forth. 70
6. In combination with the door 7, carrying hook 51, the fixed contact-plate 45, spring contact-plate 46, and movable plate of insulating material 47, substantially as described. 75
7. The combination of the spring 8, magnet 5, standards 12 and 10, armature 11, and contact-plates 53 and 13, substantially as described. 80
8. The combination of the spring 8, magnet 5, standards 12 and 10, armature 11, contact-plates 53 and 13, and latch 14, substantially as described.

WILLIAM A. BARNES.
